The ornamental design for a drip chamber cap, as shown and described.

DESCRIPTION

The patent or application contains at least one drawings executed in color photograph. Copies of this patent or patent application publication with color photograph(s) will be provided by the Office upon request and payment of the necessary fee.

FIG. 1 is a top perspective view of a drip chamber cap in accordance with the subject disclosure.

FIG. 2 is a front view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.

In the drawings, the broken lines show portions of a drip chamber cap that form no part of the claim.
